United States Patent Office

Des. 214,392
Patented June 10, 1969

214,392

PITCHER

Gerald Gulotta, New York, N.Y., assignor to Block China Company, New York, N.Y., a partnership composed of Elizabeth Block, Jay L. Block and Robert C. Block

Filed Feb. 28, 1968, Ser. No. 10,771

Term of patent 14 years

Int. Cl. D7—01

U.S. Cl. D44—21

FIG. 1

FIG. 2

FIG. 3

FIG. 4

FIG. 5

The dominant features of the design are shown in full lines.

I claim:

The ornamental design for a pitcher, substantially as shown and described.
